CLAIM

The ornamental design for a flashlight for use by physicians for mouth, ear and the like, as shown and described.

DESCRIPTION

FIG. 1 is a perspective view of a syringe-shaped, hand-held portable flashlight showing my new design;

FIG. 2 is a side elevational view thereof;

FIG. 3 is a front elevational view thereof, the rear view being identical except for the vertical clip;

FIG. 4 is a top plan view thereof;

FIG. 5 is a bottom plan view thereof;

FIG. 6 is an opposite side elevational view thereof.
